TANK CLEANING APPARATUS

Clarence C. Melton, Kansas City, Mo., assignor to
Transcontinental & Western Air, Inc., Kansas
City, Mo., a corporation of Delaware

Application July 7, 1943, Serial No. 493,739

3 Claims. (Cl. 134—150)

1

This invention relates to tank cleaning apparatus and more particularly to mechanism for cleaning oil tanks.

Aircraft engines are supplied with oil from tanks commonly mounted in wing sections, or other convenient parts of the plane. Periodically, these tanks must be removed and thoroughly cleaned to insure against clogging of feed lines and other hazardous consequences which might result from the collection of excessive sludge and dirt in the tanks.

It is the principal object of this invention to provide apparatus for thoroughly cleaning tanks of the above character in a relatively short period of time with a minimum amount of effort.

A further aim of the invention is to provide apparatus for violently agitating a tank filled with cleaning liquid.

A yet further aim of this invention is to provide mechanism for conducting flushing liquid to the tank while the latter is being agitated.

These and other objects of the invention have been accomplished with structure shown in the accompanying drawings, wherein:

Fig. 1 is a plan view of tank cleaning apparatus constructed in accordance with this invention.

Fig. 2 is a side elevational view of the cleaning apparatus.

Fig. 3 is an end elevational view of the same.

Fig. 4 is an enlarged sectional view of one end of the cradle shaft and its associated parts, taken on line IV—IV of Fig. 2.

Fig. 5 is a similar sectional view of the other end of the shaft, taken on line V—V of Fig. 2; and

Fig. 6 is an enlarged cross sectional view of the cradle and shaft taken on line VI—VI of Fig. 1.

Referring more particularly to the drawings, a support comprises an H-shaped base member 12 and a pair of spaced uprights or posts 14 and 16. Suitable bracing 18 and angles 20 are employed to produce a very rigid support, capable of withstanding the violent vibration to which it is subjected.

Uprights 14 and 16 are provided, adjacent their upper ends, with aligned transverse bearing openings 22 and 24 respectively, for receiving a cradle shaft 26. This shaft is of unique construction for a purpose which will become apparent as the description proceeds, and includes a hollow section 28 and a solid section 30. Section 28 extending through opening 22, is journaled in a bearing 32 secured to the outer face of upright 14, and a flange 34 on the shaft

2

section bears against the inner face of said upright. Similarly, shaft section 30 extends through opening 24 and is journaled in a bearing 36, secured to the outer face of upright 16, a flange 38 on section 30 engaging the inner face of the upright. The facing inner end portions 40 and 42 of shaft sections 28 and 30, are respectively offset to opposite sides of an axial line running through bearings 32 and 36, whereby 10 a line extending from one end portion to the other intersects said axial line at an angle. The inner ends of portions 40 and 42 are provided with flanges 44 and 46 respectively, between which is mounted a cradle or frame 48 having a central hollow shaft 50 aligned with said portions. The end of shaft 50 adjacent shaft section 30, is preferably plugged, as indicated at 52.

Flanged sleeves 54, surrounding shaft 50 and clamped thereon, are provided on each end of said shaft to cooperate with flanges 44 and 46 for securely mounting cradle 48 on the shaft assembly.

Frame 48 is preferably rectangular in shape and provided with a pair of intermediate cross members 56, best illustrated in Fig. 6. These cross members are constructed of duplicate sections 58, each including a laterally directed abutment 60 on one of its ends, the abutment of one section being adjacent one side edge of frame 48, while the abutment of the other section is adjacent the opposite side edge of the frame. The outer edge of each section 58, together with abutment 60, is contoured to serve as a saddle for receiving a tank 62, indicated by dotted lines 35 in Fig. 6, the contoured edge being covered with felt 64, or similar material to protect the tank.

Each tank 62 is held in position in its respective pair of saddles by band sections 66, covered throughout their tank engaging portions with felt 68 or similar non-abrasive material. One end of each band section 66 is pivotally anchored to frame 48 by a bracket 70 and its opposite end terminates in a bolt 72 adapted to be extended through an opening 74 in bracket 76 secured to abutment 60. A nut 77 bearing against a collar 78, sleeved over the outer end of bolt 72, is employed to draw band section 66 firmly against tank 62.

With a tank 62 clamped against each side of frame 48, and with the abutments arranged so that those on one side are on the ends of cross members 56 opposite to the abutments on the other side, a balanced condition of the frame and tank assembly is obtained, which is highly 55 desirable to reduce excessive vibration.

It is further desirable to provide for flushing the tanks while they are being agitated through rotation of the cradle 48. Such is accomplished by fitting a nipple 80 into the outer end of hollow shaft section 28 and joining it through a flexible sleeve 82 of rubber or the like with a pipe 84 clamped against upright 14 by a bracket 86 and having a reduced outer end 88 suitably dimensioned to enter a hose (not here shown), leading from a source of liquid supply. The nipple 80 is rotatable within sleeve 82 to permit rotation of the shaft section 28. Shaft 50 is provided with an outlet opening 90 communicating with the opening of a clamping collar 92 into which is fitted a nipple 94 in turn connected with a T 96. Elbows 98 and 100 screwed into opposite ends of the T are connected with conduits 102 and 104, which respectively lead to the two tanks mounted on cradle 48.

The outer end of shaft section 30, journaled in bearing 36, may extend through the bearing 36 or be joined in any suitable manner with a separate shaft length as shown in Fig. 5. Keyed on the outer end of this shaft length is a pulley 106 operably connected through a series of belts 108 with a sheave 110 fixed on one end of a counter shaft 112. The latter is journaled in a bearing 114 carried by a bracket 116 secured to upright 16. The opposite end of shaft 112 is provided with a relatively large sheave 118 which in turn is operably connected through belts 120 with a small pulley 122 mounted on the shaft 124 of a motor 126. A shelf 128, secured to and projecting upwardly from upright 16, is preferably provided for supporting motor 126 in a position above pulley 106.

The operation of the apparatus for cleaning tanks is relatively simple. Two empty oil tanks are clamped in the saddles on opposite sides of frame 48 and are substantially filled with a cleaning solution. By means of motor 126, the frame or cradle 48, together with the tanks clamped thereon, are rotated and the cleaning liquid is slushed against the walls of the tank. Because of the diagonal relation of the axis of the frame to that of the aligned bearings in uprights 14 and 16, liquid is slushed not only against the peripheral side walls, but also against the end walls of the tanks. This is considered an important feature since many oil tanks are provided with partitions which would prevent proper cleaning treatment of the end walls of a tank were the axis of the frame in direct alignment with the axial line of bearings 32 and 36.

After the sludge and dirt in the tanks has been dislodged from the tank wall, the cleaning fluid is drained and a hose leading from a supply of water under pressure, is attached to end 88 of pipe 84. With all plugs and closures of the tanks removed, the frame 48 is again rotated about its axis and water flowing through hollow pipe section 28 and through conduits 102 and 104, enters the tanks to flush all of the dislodged sludge and sediment therefrom.

Tanks mounted on apparatus constructed as described, can be cleaned more thoroughly and in a much shorter period of time than has been possible with methods heretofore employed.

It is conceivable that cleaning apparatus having physical characteristics other than those shown and described might be made without de-

parting from the spirit of this invention, and it is desired, therefore, to be limited only by the scope of the appended claims.

Having thus described the invention, what I claim as new and desire to secure by Letters Patent is:

1. In tank cleaning apparatus, a pair of spaced supports; a shaft mounted for rotation in the supports, said shaft having a portion between the supports disposed at an angle to the remainder of the shaft; a rectangular frame fixed on said angularly disposed portion of the shaft; oppositely directed abutments on said frame adjacent opposite side edges thereof; means for clamping a tank onto each of two opposite sides of the frame and against said abutments; and means for rotating the shaft.

2. In tank cleaning apparatus, a pair of spaced supports; a shaft mounted for rotation in the supports, said shaft having a portion between the supports disposed at an angle to the remainder of the shaft; a substantially planar frame fixed on said angularly disposed portion of the shaft; a laterally projecting abutment on the frame; means for clamping a tank on to the frame and against said abutment; and means for rotating the shaft, said frame being so fixed on said angularly disposed portion of the shaft as to support the tank entirely to one side of the axis of the shaft.

3. In a tank cleaning apparatus, a pair of spaced supports; a shaft mounted for rotation in the supports, said shaft having a hollow end section, another end section in alignment with the hollow end section, and a portion between the supports disposed at an angle to the remainder of the shaft; a substantially planar frame fixed on said angularly disposed portion of the shaft along the axis thereof; a laterally projecting abutment on the frame; means for clamping a tank onto the frame and against said abutment, said frame being so fixed on said angularly disposed portion of the shaft as to support the tank entirely to one side of the axis of the aligned end sections of the shaft; means for conducting liquid through said hollow end section to the shaft; and means for rotating the shaft about the axes of the aligned end sections.

CLARENCE C. MELTON.
